UNITED STATES PATENT OFFICE.

JOHN GLASNER, OF ESTILL SPRINGS, TENNESSEE, ASSIGNOR OF ONE-HALF TO J. K. WILLIAMS, OF FAYETTEVILLE, TENNESSEE.

LOAD LOCKING AND RELEASING MEANS FOR OVERHEAD CARRIERS.

Application filed August 15, 1921. Serial No. 492,626.

To all whom it may concern:

Be it known that I, JOHN GLASNER, a citizen of the United States, residing at Estill Springs, in the county of Franklin and State of Tennessee, have invented a new and useful Load Locking and Releasing Means for Overhead Carriers, of which the following is a specification.

This invention relates to load locking and releasing means for overhead carriers, the same being especially adapted for use in connection with trolleys or carriers employed in carrying logs, ore, or other material, it being possible by a rearrangement of some of the pulleys, to use the invention with trolleys or carriers of any make.

Another object is to provide means whereby by the manipulation of certain lines or cables forming a part of the overhead carrier apparatus, the load can be easily lifted to position and secured to the carriage and subsequently released and lowered, the drums, frictions, sheaves and lines being relieved of all strains and consequent wear and tear to which they have heretofore been subjected while the load is being carried from point to point.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a side elevation of an overhead carrier having the present improvements combined therewith.

Figure 2 is an end elevation thereof.

Figure 3 is an elevation of a slightly modified structure.

Referring to the figures by characters of reference 1 designates a supporting cable or skyline on which are mounted the grooved

wheels 2 of the carriage adapted to travel along said cable. These wheels are mounted between side plates 3 forming the body of the carriage and mounted to swing between these side plates are spaced depending levers 4 and 5 respectively. The lever 5 has a short arm extending upwardly from its pivot 6 and to this arm is pivotally connected one end of a bar 7 mounted to slide between superposed guide pins 8. Another bar 9 is pivotally connected to the lower or depending arm of the lever 4 and projects between superposed guide pins 10, the two bars 7 and 9 being extended in opposite directions and outwardly beyond the plates 3. The upper or short arm of the lever 4 is connected by a link 11 to the lower or long arm of the lever 5. Latch bars 12 are pivotally connected to the lower ends of the levers 4 and 5 and extend toward each other and are formed in the lower edges of these latches are notches 13. Supporting bolts 14 connect the plates 3 and the latches normally rest on them, the grooves or notches in the latches serving to receive the bolts so as thus to hold said latches in proper position.

Sheaves or pulleys 15 are mounted between the plates 3 below the respective latches 12 and another pulley or sheave 16 is supported between the plates 3 above the link 11 but below the line 1.

The out haul line 17 is adapted to be connected to the bar 7 while the locking line 18 is adapted to be connected to the bar 9. The load line, indicated at 19, is adapted to extend over the sheave or pulley 16, downwardly between the latches 12 and between the pulleys or sheaves 15 and is provided with a small conical weight 20.

In using the apparatus the out haul line 17 is held fast and by pulling on the line 19 the load attached thereto will be raised. During this action the conical weight will pass upwardly between the plates 3 and to position above the latches 12 so that these latches will thus support the load. Obviously as long as the carriage is being moved in either direction or while it is at rest the load will be supported. When the carriage reaches its destination, or at any predetermined

mined intermediate point where it is desired to lower the load, the line 17 is held fast and the line 19 is pulled so as to lift the weight 20 a slight distance above the latches. The locking line 18 is then pulled and will cause both latches to move apart and while they are thus located the line 19 can be paid out to lower the load. It will be obvious that while the latches 12 are supporting the load the notches 13 are in engagement with the bolts 14 thereunder so that there is no danger of the latches moving apart and accidentally releasing the load as long as the weight of the load is on the latches.

Attention is called to the fact that the bar 9 is attached to its lever 4 at a greater distance from the pivot of the lever than is the bar 7 relative to the pivot 6 of the lever 5. Consequently greater power is exerted by pulling on the bar 9 than by pulling on the bar 7 with the result that no back pull will be exerted upon the line 17 due to the moving apart of the latches. This arrangement also makes it easy to open the latches against the strain on the out haul line.

It has been found that the construction can be modified so that the load can be released without the use of the out haul line 17 and one form of structure of this type has been illustrated in Figure 3. In this form of device the walls 21 of the carriage have opposed levers 22 and 23 fulcrumed therein and terminating at their lower ends in hooks or latches 24 which extend inwardly and upwardly toward each other. A link 25 is pivotally connected to the upper end of lever 22 above its fulcrum and to the lever 23 below its fulcrum so that when one hook or latch 24 is shifted the other latch 24 will be moved in the opposite direction.

A bar 26 is attached to the carriage and to the out haul line 27 and another bar 28 is pivotally connected to the lower portion of the lever 22 and is connected to the locking line 29. A rod 30 is pivotally connected to lever 22 below its fulcrum and supports a coiled spring 31 which bears against lever 22 so as to hold said lever normally pressed toward the lever 23. Thus when the line 32 which supports the load is moved to elevate the load, the weight 33 on the line will wedge between and move to position above the latches 24, the latches being moved apart against the action of the spring 31 which, in turn, will promptly shift the latches back to position under the weight 33 so as to support the load. With this construction the weight 33 can be bell shaped so as to house the free ends of the latches while the weight is resting on said latches. Thus the latches will be held together as long as they support the load. Obviously by slightly raising the load and pulling on the line 29 the latches can be moved apart so as to release

the load. While the part 33 has been referred to as a weight, it is to be understood that this member is primarily designed as a latch engaging means and can be of any construction suitable for that purpose.

While the spring 31 has been shown with its rod 30 connected to lever 22 it will be understood of course that this spring can be located in any other place desired in order to secure the desired results.

What is claimed is:—

1. In an overhead carrier a carriage, a load line suspended therefrom, a weight thereon, opposed latches, means for moving the latches toward or from each other into position under or to release the weight respectively, an out haul line, a connection between the out haul line and the carriage adapted when the line is pulled to move the latches toward each other, and a locking line for pulling the latches apart to release the weight and load line.

2. In an overhead carrier a carriage, spaced levers fulcrumed therein, latches pivotally connected to the respective levers and extending toward each other, a connection between the levers to insure simultaneous movement of the latches in opposite directions respectively, an out haul line connected to one of the levers to move the latches toward each other when the line is pulled, a locking line connected to one of the levers for moving the latches apart, a load line suspended from the carriage and extending between the latches, and means on the load line and movable therewith to a point above the latches for resting on the latches to support a load.

3. In an overhead carrier a carriage, spaced levers fulcrumed therein, latches pivotally connected to the respective levers and extending toward each other, a connection between the levers to insure simultaneous movement of the latches in opposite directions respectively, an out haul line connected to one of the levers to move the latches toward each other when the line is pulled, a locking line connected to one of the levers for moving the latches apart, a load line suspended from the carriage and extending between the latches, and means on the load line and movable therewith to a point above the latches for resting on the latches to support a load, and means for engagement by the latches when supporting a load for holding the latches against relative movement.

4. In an overhead carrier a carriage, a load line suspended therefrom, a member thereon, spaced levers pivotally connected to the carriage, latches extending from the levers and toward each other, said load line being movable between the latches, a connection between the levers, means connected to one of the levers and operating through

said connection upon the other lever for moving the latches toward each other into position under the member on the load line, means connected to one of the levers and operating through said connection upon the other lever for moving the latches apart to release the member on the load line.

In testimony that I claim the foregoing as my own, I have hereto affixed my signature in the presence of two witnesses.

JOHN GLASNER.
